DESIGN FOR A CRIB TOY

Elmer Szantay, Chicago, Ill., assignor to Sandee
Manufacturing Company

Application March 6, 1948, Serial No. 144,955

Term of patent 14 years

(Cl. D34—15)

To all whom it may concern:

Be it known that I, Elmer Szantay, a citizen of the United States, residing at Chicago, county of Cook, and State of Illinois, have invented a new, original, and ornamental Design for Crib Toy, of which the following is a specification, reference being had to the accompanying drawing, forming a part thereof, in which—

Fig. 1 is a side elevational view of the crib toy, showing my new design;

Fig. 2 is a top plan view thereof, and

Fig. 3 is an end elevational view thereof.

I claim:

The ornamental design for a crib toy, as shown.

ELMER SZANTAY.
